REGISTERING COIN BANK

Mauray G. Malnick, Sherman Oaks, Calif., assignor of fifty per cent to Sol Moss, Los Angeles, and fifty per cent to Irvin Lynn, Beverly Hills, Calif.

Application July 30, 1949, Serial No. 107,813

29 Claims. (Cl. 235—100)

1

This invention relates to coin banks and similar coin controlled instruments, and more particularly to coin banks embodying mechanisms for cumulatively registering the value of the coins deposited in the bank.

An object of the invention is to provide an improved coin bank which automatically becomes unlocked when a preselected total value of coins is deposited in the bank.

Another object of the invention is to provide a coin bank which can be preset, at will, to different monetary values, which must be deposited in the bank before the bank will open.

A further object of the invention is to provide an indicator on a bank capable of acting as a reminder for the total amount of money that must be deposited in the bank before the latter will open. After the indicator has been set to the desired value and the bank locked, the indicator setting cannot be disturbed, either purposely or inadvertently, until sufficient money has been inserted in the bank to effect its opening.

Yet another object of the invention is to provide an indicator on a bank which acts as a reminder for the total amount of money that must be deposited in the bank to effect its opening, in which the indicator device urges the bank door, or other closure member, to open position when such door or closure member becomes unlocked.

Still another object of the invention is to provide a pawl operated registering device movable in accordance with the deposit of coins in the bank, or similar coin controlled device, in which movement of the pawl is accelerated as a result of placing larger denomination coins in the bank.

A further object of the invention is to provide a coin mechanism capable of registering dollars and cents by the aid of appropriate dials, in which movement of one of the dials to a zero position automatically shifts the other dial to zero position. More specifically, turning of the dollar dial to zero shifts the cents dial to zero.

Yet a further object of the invention is to provide a coin controlled mechanism which prevents return movement of the coin and a carrier for the coin until the carrier and coin have been moved to a predetermined position.

Another object of the invention is to provide a coin ejector arrangement in a coin controlled mechanism which ejects a coin from a coin carrier, and which also serves to hold the coin in a definite position with respect to the coin carrier. The coin ejector can hold coins of various denominations in individual and definite positions in the coin carrier.

A further object of the invention is to provide a coin controlled device embodying a guide for holding coins of different value in their respective operative positions during their travel along the

2

guide, to assure proper operation by each coin of an associated mechanism, such as the register of a portion of a bank.

Another object of the invention is to provide a coin operated device in which coins of various denominations may be inserted through a common slot and yet be properly located and guided so as to assure operation of an associated mechanism to an extent proportionate to the value of each coin.

Another object of the invention is to provide for the coupling, in various selected positions, of a door lock to a registering dial, which may form part of a registering bank.

Another object of the invention is to provide a registering bank of strong and sturdy construction, which can be manufactured at a relatively low cost.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figure 1 is a perspective view of a registering bank or safe embodying the invention;

Fig. 2 is a view similar to Fig. 1, with the door open;

Fig. 3 is a vertical section, on an enlarged scale, taken along the line 3—3 on Fig. 1;

Fig. 4 is an enlarged front elevation, with parts broken away, of a portion of the registering and indicating devices;

Fig. 5 is a vertical section, on an enlarged scale, taken along the line 5—5 on Fig. 4;

Fig. 6 is a section taken along the line 6—6 on Fig. 3;

Fig. 7 is a cross-section, on an enlarged scale, taken along the line 7—7 on Fig. 6;

Fig. 8 is an exploded isometric view of the registering mechanism, as seen from the interior of the bank;

Fig. 9 is a front elevation of a form of detent forming part of the registering mechanism;

Fig. 10 is a side elevation of the detent shown in Fig. 9;

Fig. 11 is a front elevation of a pawl and pawl operating arm, forming part of the registering mechanism;

Fig. 17 is an isometric view of the coin control mechanism, disclosing its operation upon the deposit of a quarter in the bank;

Fig. 18 is a view similar to Fig. 17, disclosing operation of the mechanism with a dime inserted therein;

Fig. 19 is a view similar to Fig. 17, disclosing operation of the mechanism with a nickel deposited therein;

Fig. 20 is a cross-section through the coin control mechanism, disclosing the apparatus with a penny deposited therein;

Fig. 21 is a section taken along the line 21—21 on Fig. 15.

A registering bank or safe is disclosed in the drawings, and includes a housing 10 defined by top and vertical walls 11, 12, and by a bottom 13 suitably secured to the vertical walls. The front wall of the housing is provided with an opening 14 adapted to be closed by a door 15. This door is provided with upper and lower hinge plates 16 having inwardly directed lugs 17 received between cooperable lugs 18 formed on the front wall at one side thereof. A hinge pin 19 is inserted through the holes 20 in all of the lugs, for the purpose of pivotally supporting the door in assembled position on the front wall of the bank or safe housing 10. The hinge pin may be inserted through a hole 21 in the bottom 13 of the housing until it extends through all of the lug holes 20, with the lower end 22 of the pin disposed immediately above the housing bottom. Thereafter, such lower end 22 may be bent slightly out of alignment with the bottom hole 21, to prevent dropping of the hinge pin and to insure its retention in place (see Fig. 6).

The door 15 carries a registering mechanism 23 for recording the value of coins deposited in the bank housing 10, and also carries a door locking device 24 that is cooperable with a generally U-shaped, spring-like latch plate 25 disposed within the housing 10 adjacent the opening 14 through the front wall. This U-shaped member 25 has a flange 26 through which a screw 27 extends, for attaching the locking plate to a frame 28 fastened to inwardly directed portions 29 of the housing, as through use of a plurality of screws 30. The door latch 24, itself, is mounted on the door 15, and will hold the door closed until a pre-selected value of coins has been deposited in the bank. When this condition is satisfied, the door latch will have been shifted to a position enabling the door to open.

The door latch 24 consists of a generally cup-shaped member having an outwardly directed flange 31 adapted to be disposed behind a finger 32 extending from the U-shaped latch member 25. This flange is circumferentially continuous around the lock 24, except for a notched or cut-out portion, or opening 33, which is registrable with the latch finger 32 upon rotation of the cup-shaped latch member. When this registration occurs, the flange 31 no longer is restrained by the latch finger, allowing the door 15 to be swung open.

The door latch member 24 is rotatably mounted on a reduced diameter portion 34 of a dial setting

knob 35, which is rotatably mounted upon a shaft 36 extending inwardly from a mounting plate 37 suitably secured to the door 15, as by being clamped thereagainst by means of the fingers 38 integral with the door, and capable of being bent over the mounting plate (see Figs. 6 to 12, particularly). Secured to an outer portion of the knob 35 is a registering dial 39 having indicia 40 on its outer face, which may register in dollars. Each dollar value is alignable or registrable with a dollar window opening 41 formed in the door. As disclosed in the specific example in the drawings, the dollar dial may have twenty indications 40 at the outer margin of its outer face indicating dollar units ranging from zero to nineteen dollars, inclusive. The periphery of this dial is also provided with twenty ratchet teeth 42 corresponding with the number of dollars than can be indicated by the dial 39.

For the purpose of insuring proper registration between the numbers 40 and the window 41, and proper intermittent advance of the dollar dial, a detent device is provided. This detent is a relatively flat, spring-like member 43 disposed over the shaft 36 and having side lugs 44 receivable within corresponding slots 45 in the mounting plate 37 on opposite sides of the shaft, in order to prevent rotation of the detent 43. At its top and bottom, the detent is provided with inwardly directed indentations or protuberances 46 adapted to be received within recesses 47 formed in the dollar dial 39 by companion indentations or protuberances 47. The dollar dial indentations 47 correspond in numbers to the number of ratchet teeth 42 and dollar indicia 40 on the face of the dial. The dial 39 may be rotated, displacing the detent protuberances 46 out of the dial recesses 47, in view of the leaf spring-like characteristics of the detent 43, the detent protuberances 46 progressively engaging in each dial indentation 47. The reception of the detent protuberances 46 in the dial indentations 47 insures appropriate registry of the dial with the window 41, and advance of the dial 39 by the proper angular extent.

The rotary door latch 24 is also provided with equiangularly spaced protuberances 48 in its base portion adapted to cooperate with the dial indentations 47, to hold the latch 24 and dial 39 releasably coupled together. A dish-like spring 49 is mounted on the knurled knob 35, with its inner portion bearing against a knob shoulder 50, and its outer portion against the lock indentations 48, urging such indentations into coupling engagement with the dial indentations 47, and insuring joint movement between the two members. However, the rotary door latch 24 may be grasped by the person's hand and turned relative to the dollar dial 39, when the device is to be set in the manner described hereinafter. Such relative rotation is permitted, since the door latch 24 may move endwise on the knob 35, as permitted by the deflection of the dished spring 49.

The inside face 39a of the dollar dial 39 may also be provided with dollar indicia that are registrable with the cut-out portion or window opening 33 in the door latch 24; so as to enable the person to set, at will, the number of dollars that must be deposited in the bank before the bank door 15 can open.

The dollar dial and door latch device may be held in assembled relation by a suitable keeper 51 disposed within a recess 52 in the outer end of the dial knob 35, with the arms 53 of the keeper received within a peripheral groove 54 at the end

of the shaft 36. The knob itself projects through an enlarged hole 55 in the frame 28; so that the door 15 may be swung between open and closed positions without interference.

The registering device also includes another dial 56 which may indicate the number of cents deposited in the bank. This cents dial may indicate cent values in increments of five cents, ranging from zero to ninety-five cents, inclusive. Its outer face may be provided with twenty divisions 57 registrable with a cents window 58 at the front of the door adjacent the dollar window 41, the indicia 57 on the cents dial indicating zero-zero cents, five cents, ten cents, fifteen cents, etc., progressively around the circumference of the dial.

The cents dial 56 is rotatably mounted on a shaft 59 fixed to and projecting inwardly from the mounting plate 37, that is secured to the door 15. This dial has protuberances 60 corresponding in number to the cents indicia 57, which form recesses 61 adapted to cooperate with a detent 62 disposed on the shaft 59 and having protuberances 63 receivable within the dial protuberances 60. This detent 62 is the same as the dollar detent 43, and cooperates with the dollar dial 39, in that it registers the cents dial so that its cents indicia 57 are disposed properly with respect to the indicating window 58 and is shifted the required angular extent.

The cents dial 56 is movable, step-by-step, by an arcuate power pawl 64 extending circumferentially along the inner face of the cents dial and secured to or integral with a pawl arm 65 that is rotatable about the shaft 59. A suitable washer 66 may be mounted on the shaft to space the pawl arm 65 from the cents dial 56. The pawl 64 on the arm 65 is engageable with a plurality of equiangularly spaced teeth 57 formed on the inner face of the cents dial. These teeth, in the specific example disclosed, are twenty in number, and correspond to the cents indications 57 on the outer face of the dial 56.

The pawl arm 65 is moved in a driving direction by a coin control mechanism to be described later, its forward or driving movement, as to the left, as seen in Fig. 6, being limited by engagement of the outer end of the arm with a suitable stationary stop 68 extending inwardly from the mounting plate 37. Rearward movement of the pawl arm and pawl is limited by engagement of the outer end of the arm 65 with another stop 69 extending inwardly from the mounting plate.

The pawl arm is normally urged in a rearward direction by a coil spring 70, the convolution of which is disposed around the hub 65a of the pawl arm, one end of the spring being hooked over a suitable lug or anchor 71, extending inwardly from the mounting plate 37, and the other end of the spring engaging the inner portion of a cam or pawl arm accelerator 72 extending axially of the pawl arm in a direction inwardly of the bank. The pawl arm 65 itself is rotatably mounted on the hub 73 of a washer 74 carried by the shaft 59, the flange of this washer engaging and confining the spring against endwise displacement. All of the assembled parts of the cents pawl and ratchet mechanism are retained in assembled position by a suitable keeper 75 fitting within a peripheral groove 76 at the inner end of the shaft 59.

As the pawl arm 65 is moved in a forward direction, its pawl 64 engages a ratchet tooth 67, and advances the dial 56 a distance corresponding to angular movement of the pawl. The dial 56 is moved by equal increments, and is centered or registered at the end of the power stroke of 75

the pawl arm 65 and pawl 64 by the indentations 63 on the detent 62 fitting within the generally concave or spherical recesses 61 in the cents dial.

In the specific device shown in the drawings, 5 the cents dial 56 is mounted in substantially the same plane and adjacent the dollar dial 39. When the cents dial has been rotated a complete revolution, or an amount equal to a dollar an outwardly projecting tooth 77 on the periphery of 10 the cents dial will engage a tooth 42 on the dollar dial, the movement of the cents dial 56 then turning the dollar dial 39 a partial revolution, such as $\frac{1}{20}$ of a revolution, to cause the dollar indication 40 to change behind the window 41, 15 and also to rotate the door latch 24 a corresponding amount, to shift its opening 33 toward the latch plate finger 32. As the pawl 64 operates to feed the cents ratchet 56 about its axis, and as the dollar ratchet wheel 39 is rotated by the 20 cents dial tooth 77 in a step-by-step fashion, the door latch 24 is also rotated and eventually brings its opening 33 in alignment with the latch finger 32, which enables the door 15 to open.

The registering device 23, and particularly the 25 pawl arm 65, is moved in a registering direction in accordance with the value of coins deposited through a slot 78 formed in the top 11 of the housing 10. As each coin is deposited through this slot, an operating handle or rod 79, forming 30 part of the coin control device within the bank, is shifted through a slot 80 in the top of the housing at right angles to the coin slot 78, to cause the pawl arm 65 and pawl 64 to be moved in a forward or ratchet feeding direction. The 35 coin control mechanism effects movement of a ratchet operator or finger 81 that extends through a horizontal slot 82 in the frame 28, and is adapted to engage the pawl arm 65 and shift it in a forward direction whenever a coin is deposited and the operating handle 79 shifted along its slot 80 and an aligned slot 89a in the frame 28. The greater the value of the coin deposited in the coin slot 78, the greater is the amount of motion imparted to the projection 81, and a correspondingly greater amount of angular movement imparted to the pawl arm 65, in order to cause the pawl 64 to advance the cents dial 56 to a greater extent.

The coin control portion of the apparatus is 40 designed to receive coins of different values and cause them to indicate properly, in cumulative fashion, the total value of coins deposited in the bank. A coin inserted through the coin slot 78 in the top 11 of the bank and through a corresponding slot 78a in the frame drops within a confined space 83 in a coin carrier 84. This coin carrier includes a top plate portion 85, to which the operating handle 79 is secured, slidably under the top 11 of the housing. The side margins 86 of this plate 85 are movable along suitable guides. One guide is formed by the top portion 87 of the frame 28 of the mechanism, and by a horizontal flange 88 of a coin guide 89, which is spaced from the top 87 of the frame by a suitable spacer bar 90, to form a groove or recess 91 for a side margin 86 of the coin carrier. The guide 89 and spacer 90 are secured to the top 87 of the frame by rivets 92, or the like, to hold the parts in assembled relation, such as disclosed most clearly in Fig. 3 and Figs. 17 to 20, inclusive.

The other side margin 86 of the coin carrier 84 is guided in a groove 93 formed by a guide plate 94 disposed below the carrier top plate 85, and spaced from the top 87 of the frame by a suitable spacer bar 95, the guide 94 and spacer

bar 95 being secured to the frame top 85 by rivets 96, or the like, such as illustrated in Figs. 3 and 20.

The forward portion of the coin carrier 84 contains a depending plate 97, integral with the top 85 of the carrier, having a vertical slot 98 therein. Spaced forwardly from this plate 97 is a second plate 99 having a slot 100 in alignment with the first-mentioned slot 98, and which is open at its lower end. The two parallel plates 97, 99 are spaced apart by an interconnecting web 101 to an extent permitting free dropping of a coin between the plates. The carrier opposite the web side 101 is open between the plates, to allow coins to engage the guide 89.

A coin dropped into the coin carrier 84 will come to rest against the web or wall 101 and also against the coin guide 89, along which the coin is slideable when the coin carrier 84 is advanced. The coin guide includes the top horizontal flange 88 heretofore described, from which the main portion 102 of the fixed guide depends, the guide being held in proper spaced relation with respect to the vertical frame wall 28 by a suitable spacer rib 103 projecting outwardly from the guide. The lower portion 104 of the guide is curved, so as to present a concave face for engagement by coins of different denominations.

As disclosed in the drawings, and particularly in Figs. 17, 18 and 19, a coin dropped into the coin carrier 84 will come to rest in different vertical positions, depending upon the diameter of the coin. One edge of the coin, as the right edge, as seen in Figs. 17, 18 and 19, will engage the side web 101 of the coin carrier, whereas another edge portion, as a left-hand edge portion, will engage the guide portion 104.

After the coin has been deposited in the carrier 84, the latter is moved in the forward direction by shifting the operating handle 79 in the slots 86, 86a, sliding the coin along the guide 104 until the coin engages one of a plurality of selector fingers 105, 106, 107 projecting inwardly by different amounts from the horizontal base portion 108 of the selector 109. The selector 109 includes a vertical portion 110, from which the pawl operator 81 projects horizontally through the horizontal frame slot 82.

When a coin is deposited in the carrier 84, it engages one of the selector fingers, and couples the selector 109 to the carrier, in order that the movement of the carrier is transmitted to the selector projection 81, which engages the generally V-shaped cam portion 72 on the pawl arm 65, to shift the pawl 64 in a cents ratchet moving direction. The amount of movement of the selector 109, and of the pawl arm 65 and ratchet 56 is dependent upon the extent of lost motion of the coin carrier 84 before the coin deposited therein engages its companion selector finger 105, 106 or 107.

The coin control device disclosed is designed to accept quarters, dimes, nickels and pennies, and to record only the quarters, dimes and nickels. A quarter 111 dropped through the coin slots 78, 78a into the coin carrier 84 will engage the coin carrier rib 101 and the curved guide 104, and be disposed in an elevated position with its left-hand portion, as seen in Fig. 17, in position for engagement with the quarter selector finger 105. This finger is disposed closest to the coin carrier 84, when the latter is in its fully retracted, or initial, position. When the coin carrier 84, with a quarter 111 deposited therein, is advanced, the quarter will engage the

quarter finger 105 and impart a maximum movement to the selector 109, causing the selector operator member 81 to engage the ratchet arm 65 and shift it angularly a distance corresponding to five teeth 67 on the cents ratchet 56, which is equivalent to an indication of twenty-five cents on the cents dial 56, as viewed through the cents window 58.

In the event that a dime 112 (see Fig. 18) is dropped through the coin slots 78, 78a and into the coin carrier 84, it will come to rest at a much lower position than the quarter 111, since it can drop downwardly to a greater extent along the curved guide 104. It comes to rest against the 15 coin carrier wall 101 and the lower edge of the guide 104. This disposes the dime in a position with its left edge further removed to the right than the quarter, no portion of the dime being in registry or alignment with the quarter finger 105, and, for that matter, with the five cent or nickel finger 107, that projects inwardly to a greater extent than the quarter finger. The lower portion of the dime, however, is in alignment with the dime finger 106, that extends from the base 108 of the selector substantially below both the quarter and nickel fingers.

The dime finger 106 is disposed between the quarter and nickel fingers 105, 107; so that the lower portion of the dime will engage the dime finger when the carrier 84 is advanced, causing a predetermined movement of the selector 109 in a registering direction. However, the coin carrier is advanced a greater distance than when it contained the quarter, before the dime engages 20 the dime finger 106. As a result, a smaller movement of the coin carrier 84 remains which is imparted to the selector 109, and results in the movement of the pawl arm 65 and pawl 64 a lesser distance, and the corresponding ratchet feeding of the cents dial 56 a lesser angular distance.

When a nickel 113 (see Fig. 9) is dropped through the common coin slots and into the coin carrier 84, it comes to rest against the right-hand web 101 of the coin carrier and also against the curved guide 104, in a position in which the nickel is disposed at a higher elevation than the dime was disposed. However, the left edge of the nickel is still disposed further to the right than the left edge of the quarter was disposed, or out of alignment with the quarter finger 105. However, the left-hand portion of the nickel is disposed in alignment with the nickel finger 107 of the selector 109. Accordingly, movement of the coin carrier 84 will occur without shifting the selector 109, until the nickel 113 engages the nickel finger 107 and shifts the selector. The amount of lost motion imparted to the coin carrier 84 before the nickel engages its selector finger is greater than for the dime, since the nickel finger is disposed a greater distance away from the coin carrier 84, when the latter is in its retracted position. Consequently, when the nickel 113 engages the nickel finger 107, the selector 109 is shifted a lesser distance, and correspondingly feeds the pawl arm 65 and pawl 64 a lesser distance, to advance the cents ratchet and dial 56 a lesser angular distance.

In the mechanism disclosed, pennies will be accepted, but will not register. Thus, the dropping of a penny 114 into the coin slot 78 and carrier 84 causes it to come to rest against the web 101 of the carrier and against the edge of the guide 104, but in a higher position than the dime. The left side of the penny, as seen in Fig. 20, is disposed a greater distance to the right than the

left side of the nickel 113 was disposed when in the coin carrier. Thus, the bottom of the penny 114 is above and out of alignment with the dime finger 106, and is also disposed to the right of and out of alignment with the nickel finger 107. Consequently, shifting of the coin carrier 84 will fail to couple the penny with any portion of the selector mechanism 109, merely sliding it along the guide 89 to the end of the latter, where the penny can drop toward the bottom of the 10 housing 10. Since the penny is incapable of coupling the coin carrier 84 to the selector 109, it cannot effect registration on the various dials.

The coin control device is also provided with a coin ejector 115, which serves to prevent return movement of the coin carrier 84 until it has been shifted to a location at which the coin is ejected into the housing chamber. The coin ejector 115 is mounted upon a hinge pin 116 secured to a pair of lugs 117 depending from the top 87 of the frame 28. From this hinge pin 116, the ejector extends in a forward direction along one side of the coin carrier 84. It has a coin engaging ratchet arm 118 extending rearwardly from the forward portion of the ejector, this ratchet arm being capable of projecting through the slots 100, 98 in the spaced coin plates 99, 97. The ejector 115 is urged in a downward direction by a tension spring 119, one end of which is secured to an upwardly directed arm 120 of the 20 ejector, and the other end of which is secured to the vertical plate 97 of the coin carrier 84. This spring not only tends to move the ejector 115 in a coin ejecting and locking direction, but it also tends to return the coin carrier 84 to its 25 initial position.

Swinging movement of the coin ejector about its hinge pin 116, or in a downward direction, by the spring 119 is limited by engagement of the forward sloping face 121 of the ejector with a cam lug or follower 122 provided at one side of the coin carrier. The cam 122 engages the sloping cam face 121 of the ejector 115 and tends to limit its downward movement. Since the ejector 115 cannot move longitudinally with the coin carrier 84, shifting of the latter in a registering direction moves its cam 122 away from the inclined cam face 121 and allows the spring 119 to urge the ejector in a downward direction about its hinge pin 116. The force of this downward movement on the ejector is increased upon movement of the coin carrier 84, in view of the increased tension that such movement imparts to the spring 119.

When the coin carrier 84 is in its initial rearward position, the inclined face 121 of the ejector engages the cam 122 and holds the ejector with the end of its ratchet 118 disposed at the entrance to the slot 100 of the forward coin carrier plate 99, and slightly above a position that the largest coin 111 occupies after it comes to rest within the coin carrier. Upon movement of the coin carrier 84, the vertical plates 97, 99 of the latter are moved with it; so as to shift the slots 98, 100 along the ratchet 118. This action disposes the coin in the carrier below the ratchet rack 118, and since the movement of the coin carrier 84 has shifted the cam 122 longitudinally away from the inclined ejector face 121, the spring 119 can shift the ratchet 118 downwardly into engagement 70 with the upper edge of the coin. This action holds the coin in its downward position with its right edge engaging the right wall or web 101 of the coin carrier, and its left edge engaging the guide 104. Since the ratchet teeth 123 on the 75

lower edge of the ratchet face in a forward direction, the coin cannot move back after it engages a ratchet tooth. Since the ratchet teeth prevent this action, this holding movement or restraint is imparted by the coin to the coin carrier 84. As a result, the coin ejector 115 holds the coin in the position to which it has come to rest in the coin carrier 84, and also prevents return movement of the carrier. It insures that the coin will engage the proper selector finger 105, 106, 107, for operating the selector 109 the predetermined amount and shifting of the registering mechanism 23.

The tension spring 119 is constantly urging the ejector 115 in a downward direction against the coin with an increasing force, as the coin carrier 84 is advanced. When the coin reaches the end of the guide 104, the ejector 115 substantially ejects the coin and shifts it downwardly within the housing. Since the return movement of the carrier has been prevented by engagement of the ratchet 118 with the coin, ejection of the coin removes the restraint on the carrier 84, and allows the tension spring 119 to return the coin carrier to its initial position, with the carrier cam 102 engaging the inclined face 121 on the ejector, re-elevating the latter and its ratchet 118 to a position in which another coin can be disposed under the ratchet.

Accordingly, it is apparent that the coin carrier 84 must be moved a full stroke, after a coin has been deposited therein, to the point where the coin is ejected, before the carrier can be returned for the reception of another coin. During such forward movement of the carrier, its top plate 85 closes the coin slot 78, 78a and precludes the insertion of another coin therein. The inability of the coin carrier 84 to be returned until the coin has been ejected insures that the particular coin deposited will cooperate properly with its companion selector finger 105, 106 or 107 to shift the selector 109 longitudinally by an amount corresponding to the value or denomination of the coin.

Since the cents dial 56 is designed to indicate a dollar amount upon a full revolution, and since the largest coin acceptable by the mechanism is a quarter, it is obvious that the quarter must effect movement of the cents dial a quarter of a revolution, or ninety degrees. Inasmuch as the selector 109 and its projecting lug 81, which engages the pawl arm 65, move in a straight line, and in view of the change in the angular position of the pawl arm as it moves in a forward direction, the engagement of the operator with a straight face on the pawl arm would cause the latter to have a relatively small angular motion imparted to it near the end of its stroke, when a quarter has been inserted in the device. As a result, the selector 109 would require shifting by a substantially greater proportionate amount to register the value of a quarter, than to register the value of a nickel or a dime.

The amount of movement of the selector necessary to register the quarter properly is reduced in the present instance by providing the cam 72 on the pawl arm 65. The outer face 125 of this generally V-shaped cam surface engages the forward edge of the selector lug 81 when the pawl arm is in the initial position. As this selector is shifted, it shifts the pawl arm 65 and pawl 64 in a ratchet driving direction, the selector lug riding off the outer cam face 125 and onto the inner cam face 126. During the first phase of the movement, the selector lug is operating on the

pawl arm at a closer distance to its radius, and therefore will impart a greater angular movement to the pawl arm 65. During the latter phases of its movement, when a quarter is in the coin carrier 84, the selector lug 81 tends to ride outwardly along the face of the pawl arm 65 and imparts a lesser angular movement to the arm, in proportion to the linear movement of the lug. However, this last-mentioned action is minimized in the present instance by the cam faces 125, 126 since the inner cam surface 126 has resulted in the movement of the pawl arm by a greater extent than if the cam 75 were absent. This amount of movement is equal to the thickness or rearward projection of the cam face 126.

Accordingly, the cam 75 has resulted in the acceleration of the pawl arm 65, and its movement to a greater angular extent in proportion to the linear movement of the selector 109. For this reason, the quarter need not be moved, after it engages its finger 105, five times the distance that the nickel is moved after it engages its lug 107, to obtain proper registration of the quarter on the cents dial 56. The selector fingers can, therefore, be disposed closer to one another and the entire mechanism made more compact.

In the use of the device, the door 15 will open when the pre-selected number of dollars represented by coins, have been deposited in the bank. The exact number of dollars, or several cents over the dollar value, can be effective to unlock the door. With the door open, the door latch 24 is rotated with respect to the dollar dial 39, by hand, until the opening 33 in the door latch is in alignment with the indication of the pre-selected number of dollars that must be placed in the bank before the door can be opened, following its closing. This action is permitted, since the latch 24 is held releasably coupled to the dollar ratchet dial 39 by the spring 49 and the indentations 47, 48.

The dial knob 35 is then grasped and the dollar dial 39 rotated until zero dollars are indicated in alignment with the dollar window 41. As the dollar dial is turned to this position, and in the event that the cents dial 56 is indicating a value more than zero cents, a tooth 42 on the dollar dial will engage the peripheral cents dial tooth 77 and shift the latter to a zero setting position automatically, after which the teeth will become unmeshed, so that continued rotation of the dollar dial 39 can have no effect on the cents dial.

When the dollar dial 39 is rotated to its zero indicating position, the door 15 can be swung to its closed position, the flange 31 on the door latch 24 engaging the sloping face of the spring latch plate 25 and shifting the latter laterally until the flange 31 moves behind the latch finger 32, whereupon the latch 25 can spring over the flange 31 and prevent opening of the door, until the door latch notch 33 is in alignment with the finger 32 once again.

Coins are then deposited into the coin slot 78, and the coin carrier 84 shifted to its fullest extent, the selector 109 moving the pawl arm 65 and ratchet 56, turning the cents dial in exact conformance with the value of the coins (other than pennies) that have been deposited in the bank. For each revolution of the cents dial 56, or deposit of a dollar in the bank, the cents dial projection 77 engages a tooth 42 on the dollar dial and shifts it a fractional revolution, such as $\frac{1}{20}$ of a revolution. This causes an indication of the total dollars deposited in the bank, and also advances the opening 33 in the door latch toward

the spring pressed latch plate 25. Eventually, sufficient money has been deposited in the bank to cause the latch opening 33 to be aligned with the plate 25, allowing the door to open and the contents of the bank removed, if desired.

For the purpose of indicating the amount of money for which the latch 24 has been pre-set, an indicator 127 may be provided on the door 15. This indicator is also availed of to assist in opening the door automatically when the predetermined quantity of money, or a little more, has been deposited in the bank. The indicator includes a dial 128 mounted on the door below the registering device 23. This dial is fixed to a shaft 129 extending through the door and having a knurled knob 130 on its outer portion. A detent 131 is fixed to the shaft 129 on the inside of the door by a keeper 132, and has outwardly projecting teeth 133 adapted to engage in circularly arranged holes 134 in the door itself. Normally, a dished spring 135, disposed around the shaft 129 and between the door 15 and the detent 131, maintains the teeth 133 of the detent out of the holes 134, allowing the dial 128 to be turned by the knob 130.

When the door 15 is opened, the detent 131 is disposed out of the door holes 134. The dial 128 can then be turned, until one of the dollar numbers 136 located around the periphery of the dial is in registry with a suitable indicating line or point 137 on the door 15. As an example, if the door mechanism has been adjusted to open when five dollars has been deposited in the bank, the dial 128 will be turned until the five dollar indication is opposite the door line 137. The door 15 is then closed, and upon being closed, the inner end of the shaft 129 engages a lug 138 fixed to the frame 28, which urges the shaft 129 and detent 131 inwardly against the action of the dished spring 135, and places the detent projections 133 within the door holes 134. So long as the door 15 is locked, the detent 131 is maintained in its holding position, which precludes tampering with the indicator dial. Accordingly, once the indicator 128 is set to the dollar value at which the door is to open, this setting cannot be changed, either purposely or otherwise.

When sufficient money has been placed in the bank to rotate the dial 39 and place the door latch opening 33 in alignment with the latch plate finger 32, the spring force of the dished spring 135 will react against the stationary frame projection 138 and reactively swing the door 15 toward open position.

A pin 139 may be provided for opening the door at any time. This pin can be inserted through a hole 140 in the bottom 13 of the housing, the pin point 141 moving between the arms of the latch plate 25 to swing the finger 32 outwardly of the latch flange 31, which unlocks the door.

It is, accordingly, apparent that a coin control and registering mechanism has been provided, in which a single slot is capable of receiving coins of various values and appropriately registering such coins, in cumulative fashion, on the registering portion of the mechanism. In addition, the registering mechanism operates a door control device which holds the door locked until a pre-selected monetary value is placed in the bank, whereupon the door is automatically shifted to open position. The mechanism insures the positive ejecting of the coins into the bank from the coin carrier, and precludes return movement of the carrier after its movement in a coin

registering direction has commenced. In addition to the foregoing, the registering mechanism is accelerated in its movements, so as to insure proper registration and recording of coins of larger value.

The inventive features disclosed herein and relating to the coin carrier and selector are both described and claimed in my divisional application Serial No. 222,646, filed April 24, 1951, for "Coin Carrier and Selector Apparatus."

The inventor claims:

1. In a coin bank: a housing member for receiving coins and having an opening; a closure member for closing said opening; a registering device for registering the value of coins deposited in said housing member; a lock element on one of said members; a latch on the other of said members and releasably fixed to said registering device to rotate with said registering device at all times during its registering movement, said latch having means thereon engaging means on said lock element for locking said closure member in closed position over said opening, said latch being movable by said registering device to a position unlatching said closure member when said registering device records predetermined value of coins deposited in said housing member; and means enabling said latch to be shifted relative to said registering device to vary the value of coins to be deposited in said housing member before said closure member can be opened.

2. In a coin bank: a housing for receiving coins and having an opening; a closure member for closing said opening; a registering device on said closure member movable in accordance with the size of coins deposited in said housing; a lock element on said housing; a latch carried by said closure member and having means thereon engaging means on said lock element for locking said closure member in closed position over said opening; and means releasably coupling said latch to said registering device to cause said latch to rotate with said registering device at all times during its registering movement, said coupling means being releasable to enable shifting of said latch with respect to said registering device to vary the movement of the registering device and latch necessary to automatically release said means on said latch from said means on said lock element to unlock the closure member when a preselected value of coins has been deposited in said housing.

3. In a coin bank: a housing for receiving coins and having an opening; a closure member for closing said opening; a registering device carried by said closure member and movable in accordance with the size of coins deposited in said housing; a lock element on said housing; a latch carried by said closure member coaxial of said registering device and having means thereon engaging means on said lock element for locking said closure member in closed position over said opening; and means releasably coupling said latch and registering device together to cause said latch to rotate with said registering device at all times during its registering movement, said coupling means being releasable to enable said latch and registering device to be angularly shifted relative to each other to preselect the value of coins to be deposited in said housing to obtain automatic release of said means on said latch from said means on said lock element to unlock said closure member.

4. In a coin bank: a housing for receiving coins and having an opening; a lock member on said housing; a rotary latch carried by said closure

member and having means engaging means on said lock member to hold said closure member locked across said opening, said latch having an opening alignable with said lock member to unlock said closure member; a registering device movable in response to the size of coins deposited in said housing; and means releasably fixing said rotary latch to said registering device to rotate with said registering device at all times during its registering movement, whereby said latch is rotated to a position aligning said latch opening with said means on said lock member, said releasable means being releasable to enable said latch to be shifted angularly relative to said registering device to preselect the value of coins to be deposited in said housing to obtain automatic release of said means on said latch from said means on said lock member to unlock said closure member.

5. In a coin bank: a housing member for receiving coins and having an opening; a closure member for closing said opening; a registering device movable in accordance with the size of coins deposited in said housing member, said registering device having indicia thereon indicating to an observer the value of coins in said housing member; a lock element on one of said members; a latch having means thereon engageable with means on said lock element for locking said closure member in closed position across said opening; means releasably coupling said latch to said registering device in order that said latch rotates with said registering device at all times during its registering movement to move said latch to an unlocking position, said registering device having indicia thereon cooperable with said latch to enable said latch to be shifted with respect to said registering device to preselect monetary values at which said closure member is to be unlocked.

6. In a coin bank: a housing for receiving coins and having an opening; a closure member for closing said opening; a registering device movable in accordance with the size of coins deposited in said housing; said device including a rotatable disc having monetary indicia on one surface of said disc visible to an observer when said closure member is closed across said opening; a rotary latch for locking said closure member in locked position across said opening, said latch having an opening enabling said closure member to open when said latch opening is moved to a predetermined position; said disc having other monetary indicia on another surface alignable with said latch opening; and means releasably coupling said latch to said disc to cause said latch to rotate with said disc at all times during rotation of said disc, said coupling means being releasable to enable said latch to be shifted angularly to various positions with respect to said disc, whereby said latch opening can be aligned with any preselected monetary indicia on said another surface at which said closure member is to open.

7. In a coin bank: a housing for receiving coins and having an opening; a closure member for closing said opening; a movable indicator which may be set, while said closure member is open, to indicate the value of coins to be inserted in said housing before said closure member can be unlocked; means shiftable by movement of said closure member to closed position for locking said indicator in its set position; and resilient means for releasing said indicator upon opening of said closure member, said resilient means urging said closing member to open position.

8. In a coin bank: a housing for receiving coins

and having an opening; a closure member for closing said opening; a movable indicator on said closure member; a member fixed to said housing; means engageable with said fixed member for locking said indicator in its set position upon closing of said closure member; and resilient means urging said indicator locking means to a released position and said closure member to open position.

9. In a coin mechanism: a housing having a coin slot; a movable coin carrier for receiving coins of different denominations inserted through said slot; a selector having a plurality of elements engageable by coins of particular denominations; means for locating coins of different denominations in individual specific positions in said carrier and in alignment with the respective corresponding selector elements, in order that movement of said carrier will shift the coin therein into engagement with its own particular selector element, and with no other selector element, to determine the extent of advance of said selector by said carrier; a registering device including a dial having indicia thereon; means including a pivoted lever for advancing said dial; said selector having an operating element for moving said lever progressively greater distances as greater values of coins are inserted in said carrier; and coengaging means on said operating element and lever for accelerating movement of said lever in a dial advancing direction, in order to decrease the movement of said selector necessary to advance said lever the angular amount proportionate to the value of a larger coin placed in the carrier, said coengaging means including a cam surface inclining outwardly and rearwardly of the direction of movement of said lever and operating element when said lever and operating element are advancing said dial.

10. In a coin bank: a housing member for receiving coins and having an opening; a closure member for closing said opening; a registering device for registering the value of coins deposited in said housing member, said device including a ratchet dial having teeth thereon and monetary indicia on a face of said dial; a lock element on one of said members; a latch movable with said dial and engageable with said lock element for locking said closure member in closed position over said opening, said latch being movable by said dial to a position unlatching said closure member when said dial records a predetermined value of coins deposited in said housing member; and means within said housing member, inaccessible from the exterior of said housing member when said closure member closes said opening, for effecting relative shifting between said latch and dial to vary the value of coins to be deposited in said housing member before said closure member can be opened.

11. In a coin bank: a housing member for receiving coins and having an opening; a closure member for closing said opening; a registering device for registering the value of coins deposited in said housing member, said device including a ratchet dial having teeth thereon and monetary indicia on a forward face of said dial; a lock element on one of said members; a latch rearwardly of and drivably connected with said dial to rotate with said dial at all times during movement of said dial, said latch having means thereon engageable with means on said lock element for locking said closure member in closed position over said opening, said latch being movable by

5 said dial to a position unlatching said closure member when said dial records a predetermined value of coins deposited in said housing member; means enabling said latch to be shifted relative to said dial to vary the value of coins to be deposited in said housing member before said closure member can be opened; one of said members having an opening forwardly of said dial through which can be observed said monetary indicia.

12. In a coin bank: a housing member for receiving coins and having an opening; a closure member for closing said opening; a registering device for registering the value of coins deposited in said housing member, said device including a ratchet dial having teeth thereon and monetary indicia on a forward face of said dial; a lock element on one of said members; a latch rearwardly of and movable with said dial and engageable with said lock element for locking said closure member in closed position over said opening, said latch being movable by said dial to a position unlatching said closure member when said dial records a predetermined value of coins deposited in said housing member; means within said housing member, inaccessible from the exterior of said housing member when said closure member closes said opening, for shifting said latch and dial with respect to each other to vary the value of coins to be deposited in said housing member before said closure member can be opened; one of said members having an opening forwardly of said dial through which can be observed said monetary indicia.

13. In a coin bank: a housing for receiving coins and having an opening; a closure member for closing said opening; a registering device on said closure member movable in accordance with the size of coins deposited in said housing; a latch carried by said closure member and rotatable with said registering device for locking and unlocking said closure member to and from said housing; and means within said housing, inaccessible from the exterior of said housing, when said closure member closes said opening, releasably coupling said latch to said registering device to enable rotation of said latch with respect to said registering device to vary the movement of the registering device and latch necessary to unlock the closure member.

14. In a coin bank: a housing for receiving coins and having an opening; a closure member for closing said opening; a registering device on said closure member movable in accordance with the size of coins deposited in said housing, said device including a ratchet dial having teeth thereon and monetary indicia on a forward face of said dial; a latch carried by said closure member rearwardly of said dial for locking and unlocking said closure member to and from said housing; means releasably coupling said latch to said dial to enable shifting of said latch with respect to said dial to vary the movement of the dial and latch necessary to unlock the closure member; said closure member having an opening forwardly of said dial through which can be observed said monetary indicia.

15. In a coin bank: a housing for receiving coins and having an opening; a closure member for closing said opening; a registering device on said closure member movable in accordance with the size of coins deposited in said housing, said device including a ratchet dial having teeth thereon and monetary indicia on a forward face of said dial; a latch carried by said closure mem-

ber rearwardly of said dial for locking and unlocking said closure member to and from said housing; means within said housing, inaccessible from the exterior of said housing when said closure member closes said opening, for releasably coupling said latch to said dial to enable shifting of said latch with respect to said dial to vary the movement of the dial and latch necessary to unlock the closure member; said closure member having an opening forwardly of said dial through which can be observed said monetary indicia.

16. In a coin bank: a housing for receiving coins and having an opening; a closure member for closing said opening; a lock member on said housing; a rotary latch carried by said closure member and having means thereon engageable with means on said lock member to hold said closure member locked across said opening, said latch having an opening alignable with said means on said lock member to unlock said closure member; a registering device movable in response to the size of coins deposited in said housing and arranged forwardly of said rotary latch; means releasably fixing said rotary latch to said registering device to rotate with said registering device at all times during its registering movement in order to rotate said latch to a position aligning said latch opening with said means on said lock member, said coupling means being releasable to enable said latch to be shifted angularly relative to said registering device; said closure member having an opening through which monetary indicia on a forward face of said registering device can be observed.

17. In a coin bank: a housing for receiving coins and having an opening; a closure member for closing said opening; a lock member on said housing; a rotary latch carried by said closure member and engageable with said lock member to hold said closure member locked across said opening, said latch having an opening alignable with said lock member to unlock said closure member; a registering device movable in response to the size of coins deposited in said housing, said registering device including a dial coaxial of and adjacent said rotary latch; and means releasably securing said latch to said dial to enable said latch and dial to be shifted angularly with respect to each other to various selected positions and then secured together in any such selected position.

18. In a coin bank: a housing for receiving coins and having an opening; a closure member for closing said opening; a lock member on said housing; a rotary latch carried by said closure member and engageable with said lock member to hold said closure member locked across said opening, said latch having an opening alignable with said lock member to unlock said closure member; a registering device movable in response to the size of coins deposited in said housing, said registering device including a dial coaxial and forwardly of said rotary latch; means releasably securing said latch to said dial to enable said latch and dial to be shifted angularly with respect to each other to various selected positions and then secured together in any such selected position; said closure member having an opening forwardly of said dial through which monetary indicia on a forward face of said dial can be observed.

19. In a coin bank: a housing member for receiving coins and having an opening; a closure member for closing said opening; a lock member on one of said members; a rotary latch on the other of said members and engageable with said lock member to hold said closure member locked

across said opening, said latch having an opening alignable with said lock member to unlock said closure member; a registering device movable in response to the size of coins deposited in said housing, said registering device including a dial coaxial of and adjacent said rotary latch; and means releasably securing said latch to said dial to enable said latch and dial to be shifted angularly with respect to each other to various selected positions and then secured together in any such selected position.

20. In a coin bank: a housing member for receiving coins and having an opening; a closure member for closing said opening; a lock member on one of said members; a rotary latch on the other of said members and engageable with said lock member to hold said closure member locked across said opening, said latch having an opening alignable with said lock member to unlock said closure member; a registering device movable in response to the size of coins deposited in said housing, said registering device including a dial coaxial and forwardly of said rotary latch; means releasably securing said latch to said dial to enable said latch and dial to be shifted angularly with respect to each other to various selected positions and then secured together in any such selected position; one of said members having an opening forwardly of said dial through which monetary indicia on the forward face of said dial can be observed.

21. In a coin mechanism: a registering device including a dial; means including a pivoted lever for advancing said dial; a coin operated device including a member movable progressively greater distances as greater values of coins are placed in said coin device; and coengaging means on said lever and member for causing said member to accelerate movement of said lever in a dial advancing direction when greater values of coins are placed in the coin operated device, said coengaging means including a cam surface inclining outwardly and rearwardly of the direction of movement of said lever and member when said lever and member are advancing said dial.

22. In a coin mechanism: a registering device including a dial; a coin operated device including a slide member movable progressively greater distances as greater values of coins are placed in said coin device; means including a pivoted lever for advancing said dial, said lever being swingable from obtuse to acute angular relations to the path of movement of said slide member to move said dial greater arcuate extents when greater values of coins are to be registered on said dial; and coengaging means on said member and lever for causing said member to shift said lever by an accelerated amount when greater values of coins are placed in the coin operated device and when said lever makes an acute angle with the path of movement of said slide member, said coengaging means including a cam surface inclining outwardly and rearwardly of the direction of movement of said lever and slide member when said lever and slide member are advancing said dial.

23. In a coin mechanism: a registering device including a ratchet dial; a pivoted arm; a pawl on said arm engageable with said ratchet dial to advance said dial in step-by-step fashion; a coin operated device including a member movable progressively greater distances as greater values of coins are placed in said coin device; and coengaging cam means on said member and

arm for causing said member to accelerate movement of said arm and pawl in a dial advancing direction when greater values of coins are placed in the coin operated device, in order to decrease the movement of said member necessary to advance said arm the required amount proportionate to the value of a large value coin placed in the coin operated device, said cam means including a cam surface inclining outwardly and rearwardly of the direction of movement of said arm and member when said arm and member are advancing said dial.

24. In a coin mechanism: a registering device including a ratchet dial; a coin operated device including a slide member movable progressively greater distances as greater values of coins are placed in said coin device; a pivoted arm; a pawl on said arm engageable with said ratchet dial to advance said dial in step-by-step fashion; said arm being swingable from obtuse to acute angular relations to the path of movement of said slide member to move said dial greater arcuate extents as greater values of coins are to be registered on said dial; and coengaging cam means on said member and arm for causing said member to shift said arm by an accelerated amount as greater values of coins are placed in the coin operated device and when said arm makes an acute angle with the path of movement of said slide member, in order to decrease the movement of said slide member necessary to advance said arm the angular amount proportionate to the value of a larger value coin placed in the coin operated device, said cam means including a cam surface inclining outwardly and rearwardly of the direction of movement of said arm and slide member when said arm and slide member are advancing said dial.

25. In a coin mechanism: a registering device including a ratchet dial; a pivoted arm; a pawl on said arm engageable with said ratchet dial to advance said dial in step-by-step fashion; a coin operated device including a member movable progressively greater distances as greater values of coins are placed in said coin device; and a cam on said arm engaged by said member for causing said member to accelerate movement of said arm and pawl in a dial advancing direction when greater values of coins are placed in the coin operated device, in order to decrease the movement of said slide member necessary to advance said arm the angular amount proportionate to the value of a large value coin placed in the coin operated device, the surface of said cam contacted by said member inclining radially outwardly and rearwardly of the direction of movement of said arm and member when said arm and member are advancing said dial.

26. In a coin mechanism: a registering device including a ratchet dial; a coin operated device including a slide member movable progressively greater distances as greater values of coins are placed in said coin device; a pivoted arm; a pawl on said arm engageable with said ratchet dial to advance said dial in step-by-step fashion; said arm being swingable from obtuse to acute angular relations to the path of movement of said slide member to move said dial greater arcuate extents as greater values of coins are to be registered on said dial; and a cam on said arm engaged by said slide member for causing said member to shift said arm by an accelerated amount as greater values of coins are placed in the coin operated device and when said arm makes an acute angle

with the path of movement of said slide member, in order to decrease the movement of said coin operated device necessary to advance said arm the angular amount proportionate to the value of a larger value coin placed in the coin operated device, the surface of said cam contacted by said slide member inclining radially outwardly and rearwardly of the direction of movement of said arm and slide member when said arm and slide member are advancing said dial.

27. In a coin bank: a housing for receiving coins and having an opening; a closure member to be locked to said housing in closed relation across said opening; a movable indicator on said closure member; a member fixed to said housing; means connected to said indicator and engageable with said fixed member to secure said indicator to said closure member in a set indicating position upon closing of said closure member; and resilient means urging said indicator securing means to a released position and said closure member to open position.

28. In a coin bank: a housing for receiving coins and having an opening; a closure member to be locked to said housing in closed relation across said opening; a movable indicator on the exterior of said closure member which may be set, while said closure member is open, to indicate the value of coins to be inserted in said housing before said closure member can be unlocked; a detent secured to said indicator; and means secured to said housing and engageable with said detent to shift said detent to indicator locking position against said closure member upon movement of said closure member to closed position.

29. In a coin bank: a housing for receiving coins and having an opening; a closure member to be locked to said housing in closed relation across said opening; a movable indicator on the exterior of said closure member which may be set, while said closure member is open, to indicate the value of coins to be inserted in said housing before said closure member can be unlocked; a detent secured to said indicator; means secured to said housing and engageable with said detent to shift said detent to indicator locking position against said closure member upon movement of said closure member to closed position; and spring means urging said detent to a position releasing said indicator for movement.
